US0D1108281S

(12) **United States Design Patent** (10) **Patent No.:** **US D1,108,281 S**
(45) **Date of Patent:** **** Jan. 6, 2026**

(54) **FREESTANDING TEMPERATURE CONTROLLER**

(71) Applicant: **MOLD-MASTERS (2007) LIMITED**, Georgetown (CA)

(72) Inventor: **Philip Kench**, Herefordshire (GB)

(73) Assignee: **MOLD-MASTERS (2007) LIMITED**, Georgetown (CA)

(**) Term: **15 Years**

(21) Appl. No.: **29/934,243**

(22) Filed: **Mar. 25, 2024**

(51) LOC (15) Cl. **10-04**

(52) U.S. Cl.

USPC **D10/50**

(57) **CLAIM**

The ornamental design for a freestanding temperature controller, as shown and described.

DESCRIPTION

FIG. 1 is a front perspective view illustrating a freestanding temperature controller;

FIG. 2 is a rear perspective view of the freestanding temperature controller;

FIG. 3 is a front elevation view of the freestanding temperature controller;

FIG. 4 is a rear elevation view of the freestanding temperature controller;

FIG. 5 is a right side elevation view of the freestanding temperature controller;

FIG. 6 is a left side elevation view of the freestanding temperature controller;

FIG. 7 is a top plan view of the freestanding temperature controller; and,

FIG. 8 is a bottom plan view of the freestanding temperature controller.

The broken lines in the drawings depict environment that forms no part of the claimed design.

1 Claim, 8 Drawing Sheets
